UNITED STATES PATENT OFFICE

165,888

GAME BOARD

Eddie P. Truesdale, Rock Hill, S. C.

Application August 22, 1951, Serial No. 16,401

Term of patent 14 years

(Cl. D34—5)

To all whom it may concern:

Be it known that I, Eddie P. Truesdale, a citizen of the United States of America, residing at Rock Hill, in the county of York and State of South Carolina, have invented a new, original, and ornamental Design for a Game Board, of which the following is a specification, reference being had to the accompanying drawing, forming part thereof.

Fig. 2 is an edge elevational view.

I claim:

The ornamental design for a game board, as shown.

EDDIE P. TRUESDALE.
